AUTOMATIC SAFETY-VALVE FOR WATER-GAGES.

981,370.

Specification of Letters Patent. Patented Jan. 10, 1911.

Application filed December 13, 1909. Serial No. 532,830.

To all whom it may concern:

Be it known that I, WILLIAM H. BRAY, of Manchester, in the county of Hillsboro and State of New Hampshire, a citizen of the United States, have invented a new and useful Improvement in Automatic Safety-Valves for Water-Gages, of which the following is a specification.

The purpose of such automatic safety valves is to close immediately upon the breaking of a water gage in order to prevent the issue from the boiler of hot water or steam to the injury of the engineer. So far as I know, in no case has there ever been constructed what I would term a duplex valve, that is, two valves working together for this purpose so that if one valve fails to work by any accident the other valve will surely close. Such a valve I have shown in the drawings applied to a water gage, it being understood that in practice two of these valves will be used, one being located at the upper end of the water gage and one at the lower. The valve in the drawings is shown as located at the lower end of the water gage.

In the drawings where the preferred form of my invention is shown—Figure 1 is a view partly in elevation and partly in section, the section including the new valve in its open position. Fig. 2 is a section on line 2—2 of Fig. 1, the valve in this case however being closed.

A is a casting containing a chamber a which is connected to the boiler by a passage a^1 . This casting also serves to support the base a^2 of the water gage a^3 and contains a passage connecting the chamber a with the interior of the water gage as is usual with such valves.

a^4 is one of the rods by which the water gage is clamped in place. The end of the casting A is threaded as at A^1 and is screwed into a coupling B which is screwed into an opening in the boiler plate B^1 . The passage a^1 continues through the coupling B as at b and is enlarged to form a valve seat b^1 for the valve C. It also comprises a tubular extension B^2 within which the valve mechanism operates, the outer end of this extension flaring as at b^2 to form a seat for the secondary valve D. It also has a flange b^3 to assist in confining the movements of the valve D as will be below described. The valve C has a stem c . The valve D also has a stem D^1

which is connected thereto by a screw d and set nut d^1 . The stem D^1 of the valve D has a chamber d^2 in its forward end which is perforated as at d^3 , the stem being of somewhat less diameter than the passage in the tubular extension B^2 to allow the free passage of water or steam through the tubular extension and into the water gage a^3 when the valves are open.

The diameter of the front end of the chamber d^2 is contracted somewhat and is threaded as at d^4 about its interior. Its threads coöperate with the threads c^1 on the enlarged rear end of the valve C. By means of these threads the enlarged end of the valve C may be screwed into the chamber d^2 as shown in the drawings so that when in place the valve C may have a movement in relation to the valve D and its stem.

The rear end of the valve D has a flange D^2 which is perforated to receive bolts D^3 which pass through it from the flange b^3 of the tubular extension B^2 of the coupling B. By means of nuts D^4 on the ends of these bolts the rearward travel of the valve D is controlled.

The casting A carries a threaded neck A^2 as is usual in devices of this character and within this threaded neck travels the stem A^3 operated by the hand wheel A^4 . It carries a rod a^5 sufficiently long to engage the forward surface of the valve C so as to push or lift it off its seat, in which case, the valve C engaging the forward end of the valve stem D^1 will lift the valve D off its seat. The apparatus is then in its normal working order, that is to say, there will be then formed a free passage for water from the boiler to the water gage a^3 and at the same time the water will fill the chamber d^2 with in the valve stem D^1 . The same operation will take place in the corresponding valve at the other end of the water gage and the parts being under balanced pressure the valves in both devices will remain off their seats. The hand wheels A^4 in both devices are then turned to withdraw the stems a^5 from engagement with the valves C and the valves will remain open until by the breaking of the water gage or by reason of any other leakage the balance is disturbed. The rush of water under these circumstances will close the valve C, the cylindrical chamber

*d*² in the valve stem D¹ exposing the entire rear surface of the valve C to pressure so that under ordinary circumstances this valve will be closed instantly. But should the 5 valve not close through any accident or the deposit of any sediment on its seat, the valve D being subjected to the same unbalanced pressure at its rear will close instantly, in its forward movement perhaps forcing the 10 valve C to its seat.

So far as I know, this is the first valve apparatus in which as an additional precaution a second valve is used reinforcing or requiring the operation of the first and 15 it will be evident to those skilled in the art that this broad idea may be embodied in other ways than that shown. I therefore do not mean to limit myself to this exact construction, nor do I mean to limit my 20 invention necessarily to use with water gages as it may be applied to other uses.

The end *a*⁶ of the stem A³ is preferably enlarged to act as a stop to engage the opposing wall of the chamber *a* when the valve C 25 is to be lifted off its seat and so prevent the person adjusting the valve C from advancing the rod *a*⁵ so far through the valve seat as to injure the rod or the valves.

For convenience the terms "rear" and 30 "front", and words of similar import, are employed to designate, respectively, positions or directions toward and away from the interior of the boiler or other source of fluid pressure with which the device is used.

35 What I claim as my invention is:

1. An automatic safety valve device comprising two freely moving valves each having a seat, said valves being located one in the rear of the other, and means connecting 40 said valves permitting a free, limited movement thereof in both directions with relation to each other, as set forth.

2. An automatic safety valve comprising two valve seats located in the same axial line 45 and two freely moving valves each having a limited movement with relation to the other and each adapted to close on its own seat independently of the other, means for opening one of said valves, and means for causing 50 said last-named valve to open the other of said valves.

3. In an automatic valve mechanism, a front valve seat, a rear valve seat and two valves, the rear valve having a stem projecting forwardly and having a chamber in its forward end, the front valve having a stem projecting rearwardly into said chamber, and means whereby the stem of said front valve is retained within said chamber but is 60 allowed to move with relation thereto.

4. In an automatic safety valve mechanism, two valves, one having a stem projecting forwardly and having a chamber in its forward end, the walls of said chamber being perforated, the other of said valves having a stem projecting rearwardly within said chamber whereby fluid pressure to close said forward valve will be applied to an area as great as the entire rear surface of 65 said valve. 70

5. In a safety valve mechanism, two valves in line, the rear valve having a stem projecting forwardly, said stem having a chamber in its front end the walls of which are contracted and threaded near its front, the 75 forward of said valves having a stem projecting rearwardly and carrying a threaded enlargement at its rear end adapted to be screwed through the threaded end of the rear valve stem, whereby said enlargement 80 may pass into the chamber in the rear stem and thereafter have a limited motion with relation thereto.

6. In an automatic safety valve mechanism, two valves in line, the forward valve 85 having a limited movement with relation to the rear valve, and rear valve having a limited movement with relation to the forward valve, and means for adjusting the extent 90 of movement of the two valves with relation to each other.

7. In an automatic safety valve mechanism, two valves in line capable of limited movement with relation to each other, and means for adjusting the extent of said movement, and means for adjusting the extent of 95 movement of the rear valve as set forth. 100

8. In an automatic safety valve mechanism a coupling provided with a valve seat and a tubular extension surrounding said seat and carrying a second valve seat at its rearward end, in combination with freely moving valves adapted independently to close against said seats and having a limited movement with relation to each other, as 105 described.

9. In an automatic safety valve of the kind described, a coupling provided with a valve seat and a tubular extension surrounding said seat and carrying a second valve 110 seat at its rearward end, freely moving valves for closing said valve seats and means adapted to engage the forward valve to open it and cause it to engage and open the rearward valve as set forth.

WILLIAM H. BRAY.
